INTERNAL-COMBUSTION ENGINE.

1,161,464.

Specification of Letters Patent. Patented Nov. 23, 1915.

Application filed November 27, 1906. Serial No. 345,360.

To all whom it may concern:

Be it known that I, GIOVANNI ENRICO, engineer, of 35 Corso Dante, Turin, Italy, have invented certain new and useful Improvements in Internal-Combustion Engines, of which the following is a full, clear, and exact specification.

Internal combustion engines are not, as a rule, provided with devices for reversing the direction of their motion because, when the direction of their motion is reversed, the reversal passes through the speed zero and the engine stops. Therefore, as internal combustion engines require to be specially started, it is impossible to pass directly from forward running to backward running, and this is a very serious disadvantage in engines used for automobiles, boats, and the like.

This invention has for its object to provide an arrangement whereby internal combustion engines can be caused to rotate in either direction and whereby they start automatically, that is they do not require to be specially started as hitherto.

In the accompanying drawings Figure 1 is a general view of an internal combustion engine provided with an arrangement in accordance with this invention. Figs. 2 and 3 represent, respectively, a section and a plan of a detail, and Fig. 4 shows a section of the same detail with its adjuncts at right angle to Fig. 2.

The engine is presumed to have four cylinders, although, to simplify the drawing, the right hand cylinders have been omitted. The invention can however be applied to engines with other numbers of cylinders.

The exhaust valves a' and a'' are operated by cams c c' mounted on the shaft b driven by the engine through the gear wheel d . The shaft b carrying the cams can be slid longitudinally in its bearing by means of an operating lever f actuated from outside either by hand, or foot. Each cam is provided with two inclined parts c' and e' , c'' and e'' running in opposite directions and connected by a suitable curve. The cams c c' act against the stems of the exhaust valves a' a'' and by shifting the shaft b by means of a lever f , either the inclined parts c' and c'' or the inclined parts e' and e'' are brought under the valve stems and the direction of rotation of the engine can thus be reversed.

In the middle of the shaft b is mounted a helical wheel g gearing with a helical wheel h mounted on a shaft p carrying a distributing valve q in a chamber i connected by a tube n to a pipe leading from a supply of compressed air not shown.

The valve q forms a close joint with, and can turn on, the bottom of the chamber i ; the said bottom being provided with four holes 1, 2, 3, 4, communicating respectively with the tubes j' , j'' , j''' , j'''' supplying the compressed air to the respective cylinders. Check valves,—three, marked v' , v'' , v''' , only are shown—are attached to the cylinders in the vicinity of the exhaust valves. The valve q is of circular disk shape and is provided with an opening r so that, during the rotation of the said valve, the said opening uncovers the holes 1, 2, 3, 4, successively and thereby establishes communication between the distributing chamber i ,—through one, or other, of the pipes j' , j'' , j''' , j'''' —and the cylinder corresponding to the uncovered hole.

The dimension of the hole r is such that each hole 1, 2, 3, 4, is uncovered only during the working stroke of the cylinder corresponding to each hole and thus, the chamber i being in communication by the tube n with the compressed air pipe, the engine can be started by the action of the compressed air which is distributed successively to the cylinders during their working phases. If the combustion of the gases in the cylinders takes place at the same time as the supply of compressed air, and a pressure higher than that of the air results therefrom, the check valves v' , &c. come into action and interrupt the admission of compressed air so that the engine then runs normally. When the rotation of the engine is reversed, the position of the opening r must be modified, because, if a piston is moving on its suction or working stroke and engine be reversed, the said piston must then effect the opposite phases, namely compression or exhaust. Consequently, when the engine is reversed, the opening r must leave that one of the holes 1, 2, 3, 4, which it is then opposite and come over the hole which corresponds to the opposite phase. This result is obtained by suitable selection of the diameters of the wheels g and h and of the pitch of their teeth, so that the sliding of the wheel g on the wheel h , which takes place when the shaft b is longitudinally

shifted to reverse the engine causes the shaft *p* and valve *q* to rotate thereby bringing the opening *r* into coincidence with the proper hole.

5 The mode of operation of the engine is as follows: The engine being at a standstill, it is started by opening the communication between the pipe *n* and the compressed air supply. The engine starts under the action 10 of the compressed air which mixes with the gases contained in the cylinders. After a few turns, or fractions of a turn, the engine is in motion and the igniting device is set to work and the engine works in the usual 15 manner and the communication between the tube *n* and the compressed air can be cut off. When the engine is reversed, this communication can be re-opened so that, at the moment the engine passes the zero of speed compressed air comes into action and causes the 20 engine to run backward. As the valve *q* only does useful work during the starting periods, it is advisable to use some arrangement that keeps it off its seat during the 25 normal running of the engine so as to avoid useless wear of the said valve and its seat. This can be effected for instance by a spring *s* acting on the stem *l* of the valve *q*, so as to tend to keep the said valve a little distance from its seat. The amount of this lift 30 is regulated by the sleeve *u* keyed on the stem *l*, and in which the shaft *p* can slide, striking, at the end of the lift, against the projection from the plate *z*. By suitably 35 adjusting the spring *s*, the compressed air introduced by the pipe *n* into the chamber *i* causes the valve *q* to descend onto its seat against the action of the spring *s*, while, as soon as the supply of compressed air is interrupted, the spring *s* lifts the valve *q* 40 from its seat. The inlet valves of the engine—which are not shown in the drawings—are operated by a cam-shaft similar to the shaft *b* and capable of sliding lengthwise, but not provided with connections with 45 the compressed air distribution.

Having now particularly described and ascertained the nature of my said invention and in what manner the same is to be performed I declare that what I claim is:

1. In an internal combustion engine, a plurality of cylinders, valve mechanism for admitting compressed gas to a plurality of said cylinders at predetermined intervals timed with relation to the piston stroke, means for operating said valve mechanism, and means for shifting said valve operating means a predetermined angular amount to admit compressed air to reverse the engine, 55 said mechanism comprising a longitudinally movable worm meshing with a rotatable worm fixed against longitudinal movement, said rotatable worm being connected to shift the valve.

65 2. In an internal combustion engine, a

plurality of cylinders, a rotary valve for distributing compressed fluid thereto at intervals timed with relation to the strokes of the pistons, and means for shifting such valve forwardly or backwardly independently of its normal rotative movement when the running direction of the engine is reversed.

3. In an internal combustion engine, a distributing device adapted to supply a compressed fluid to the cylinder at intervals timed with relation to the stroke of the engine, said device including a rotating valve, and means for shifting the position of such valve independently of its normal rotative 80 movement to reverse the engine.

4. In an internal combustion engine, the combination with a plurality of cylinders, of a cam shaft carrying double cams, each cam adapted to operate a valve in each cylinder, means for shifting said cams to change the time of opening of said valves, means adapted to supply compressed air to the cylinders, and a connection comprising a pair of meshing worms, one being longitudinally 90 shiftable relatively to the other and controlling the air valve for controlling said compressed air supply.

5. In a multiple cylinder internal combustion engine, the combination with valve 95 mechanism for controlling a compressed air supply to a plurality of cylinders timed with the piston strokes of said cylinders, of a cam operated valve for said cylinders, a double cam for each valve, and means for angularly shifting said cams and operating said air controlling valve mechanism, comprising a longitudinally movable shaft carrying said cams and a worm, and a second worm meshing therewith for controlling the 100 air supply and rotated by said longitudinal movement.

6. In an internal combustion engine, a cam shaft having cams adapted to operate the valves of a plurality of cylinders either during forward or reverse running of the engine, means for moving said cams axially to reverse the engine, a rotary distributing device for a compressed fluid connected with the cylinders, and adapted to supply compressed fluid thereto in predetermined order, and connections between said cam shaft and said distributing device adapted to alter the operation of said device when the cam shaft is in its reversing position.

7. In an internal combustion engine, a reversing mechanism including a distributing device adapted to supply a compressed fluid to the cylinder at intervals timed with relation to the stroke of the engine, means for changing the operation of such device to reverse the engine, and means for operating the exhaust valves during the reverse running of the engine, said means being connected with the means for changing the op- 120 125 130

eration of the distributor so that they operate together, said connections comprising worm wheels, one of which is adapted to be moved non-rotatively to shift the other.

5 8. In an internal combustion engine, a reversing mechanism including a distributing device adapted to supply a compressed fluid to the engine at intervals, such distributing device including a rotating valve adapted 10 to cover and uncover ports leading to the cylinder, and means for holding said valve unseated during normal running of the engine.

9. In an internal combustion engine, the 15 combination of a plurality of cylinders, exhaust valves therefor, means for operating said exhaust valves, means for reversing the operation of said exhaust valves, a distributing device for compressed air comprising a 20 rotary valve having ports leading to the several cylinders, check valves adapted to prevent return flow through said ports, a worm wheel for operating said rotary valve, and a worm connected with the valve operating 25 mechanism for rotating said worm wheel.

10. The combination in a combustion engine with a rotary shaft, and a valve operated thereby, of a worm for rotating said shaft, a second shaft carrying a worm meshing 30 with said first shaft, cams on said latter shaft having a plurality of separated operating surfaces, valves operated by said cams, and means for longitudinally moving said second shaft, cams and worm carried there- 35 by to displace said cams relatively to the valves operated, and to rotate said first named shaft.

11. The combination with a combustion engine having a piston and mechanically 40 operated inlet and exhaust valves, of means for longitudinally shifting the operating cams of said valves to reverse the engine, a source of compressed gas, a distributing valve controlling said compressed gas supply, and means for operating said distributing 45 valve to admit air to the cylinders simultaneously with the shifting of said cams.

12. An auxiliary fluid pressure starting device for a multi-cylinder engine consisting 50 of a traveling valve adapted successively to open ports communicating with the cylinders, the opening of the ports following the normal firing sequence; and means for shifting said valve to close the port which stands 55 open, and to open a port communicating with a different cylinder whereby the engine can be started in the reverse direction.

13. An auxiliary fluid pressure starting device for a six cylinder engine consisting of 60 a traveling valve adapted successively to open ports communicating with the cylinders, the opening of the ports following the

normal firing sequence, and the traveling valve being arranged to keep each port open during substantially the entire normal working stroke of each piston; and means for shifting said valve to close the open port and open a port communicating with a cylinder in which the piston is on its compression stroke.

70 14. In a fluid pressure starting device for an internal combustion engine, the combination with the cylinders each provided with an inlet port; of valve mechanism adapted to be actuated by the engine to open said ports successively during the normal working strokes of the pistons; and means for changing the relation of said valve mechanism to the cylinder inlet ports to reverse 75 the engine.

15. In a fluid pressure starting device for an internal combustion engine, the combination with the cylinders, each provided with an inlet port; of a traveling member for successively opening said ports during the 80 normal working stroke of the piston in each cylinder; and means for changing the relation of said traveling member to the cylinder inlet ports to reverse the engine.

16. In an internal combustion engine, a 85 plurality of cylinders, a rotary valve for distributing compressed fluid thereto at intervals timed with relation to the strokes of the pistons, and a check valve in each of said starting passages and opening toward 90 the cylinder, for closing said passages upon increase of cylinder pressure, and means for shifting such valve forwardly and backwardly independently of its normal rotative movement when the running direction of 95 the engine is reversed.

17. In an internal combustion engine, a 100 plurality of cylinders having means for admitting and exhausting gases, during the normal operation of the engine, a separate 105 inlet passage to each cylinder having a connection with a source of starting fluid, said passages being connected to a common valve chamber, and a rotary valve driven in synchronism with the working pistons for distributing starting fluid to said cylinders at intervals timed with relation to the strokes of the pistons, said rotary distributing valve being normally unseated to relieve the friction, but being seated to control said passages upon admission of the fluid pressure to said valve chamber.

110 In witness whereof, I have hereunto signed my name in the presence of two subscribing witnesses.
